ROTARY DIE CREEPING MECHANISM FOR
CORRUGATED PAPERBOARDNels A. Anderson, Stockton, Calif., assignor to:
Fibreboard Products Inc., San Francisco, Calif.,
a corporation of Delaware

Application April 13, 1945, Serial No. 588,224

7 Claims. (Cl. 93—58.1)

1.

My invention relates to the creasing of corrugated paperboard adapted for folding into boxes, cartons or the like, and more particularly to roller die creasing of such paperboard.

Corrugated paperboard generally comprises one or more corrugated layers of paper adhesively united to flat or plane layers, the latter usually forming the outside surfaces of the paperboard. Scoring or creasing of corrugated paperboard offers a problem, particularly when the creasing is in a direction substantially parallel to the corrugations in such paperboard.

Usually, the paperboard is creased in a machine which is also provided with cutters or slotters, and means to apply print to the board if so desired; and after leaving the machine, the paperboard may be folded into boxes or cartons.

In such type of machine, it has heretofore been customary to effect the creasing by formation of a so-called "knife crease," by means of cooperating rollers, one of which has a smooth peripheral surface and another of which has an annular knife edge scoring or cutting member rotatable relative to such surface, and which scores the paperboard as it travels between the knife edge and such surface. The score which is obtained by such mechanism is not all to be desired, particularly where the score is substantially parallel to the direction of the corrugations. This is so because the flutes of the corrugations do not always run true, and the scoring knife forms a relatively narrow score line. As a result, the score may "break" either to one side or the other of the score line when the board is folded into box form; and a more or less crooked or wavy fold or hinge-line connection may thus be formed.

Such crooked hinge connection causes the portions of the sides of the formed box or carton to bulge adjacent the score, making for an unsightly container, and one which is not true. Not only are bulging sides objectionable because of the unsightly appearance they create, but also because they result in a structure which does not have the strength that exists in containers having true, non-bulging sides.

A so-called "bar crease" formed by cooperating male and female die members, mounted for relative reciprocating movement in substantially the same plane, is used commercially today for creasing solid or non-corrugated paperboard. Such die mechanism forms a true and clean crease in solid paperboard because of the positive indentation of the material along a substantial width thereof, resulting in non-bulging of the sides adjacent the crease when the board is folded,

and consequently, true corners. However, heretofore, a satisfactory crease of this character by rotatable rollers having cooperating male and female die portions to form the herein designated "roller die crease" corresponding to a "bar crease," has not been obtainable on corrugated paperboard, particularly when the creasing is in a direction substantially parallel to the corrugations. In prior attempts to roller die crease corrugated paperboard, tearing has occurred because, among other factors, an extremely high pressure and stretching are imparted to the material by virtue of the penetration thereof into the female die member which is effected by the male die member.

My invention is designed to overcome this problem of roller die creasing corrugated paperboard; and it has as its objects, among others, the provision of an improved apparatus and method for roller die creasing corrugated paperboard, and a resulting improved crease in such paperboard. Other objects of my invention will become apparent from a perusal of the following description.

In general, I have found that in order to roller die crease corrugated paperboard successfully, it is important that the roller dies, particularly the roller carrying the male die, be of sufficiently large diameter, so as to provide a length of roller contact on the material between the dies, sufficient to allow gradual indentation of the material as it passes between the dies, and thereby obviate tearing or rupturing of the board. In other words, the material should be compressed gradually as it feeds between the dies, in order to avoid too great an application of pressure at one time over a small area, which may result in tearing or rupturing of the material. Such roller contact length for any given over-all thickness of the corrugated paperboard, will increase with increase in diameter of the male roller die. Therefore, the larger the roller, the greater will be the roller contact length. In this connection, I have found, as will be pointed out more fully hereinafter, that the roller die mechanism should be of a diameter at least sufficient to provide a roller contact length of at least five (5) times the over-all thickness of the corrugated paperboard.

Another important factor is that the shafting upon which the roller dies are mounted, be of sufficiently large diameter or so piloted, that it will have substantially no flexing or vibration during rotation thereof. Otherwise, tearing or rupturing of the material might occur as it is fed by the roller dies, by virtue of periodic high pressures

which would be placed on the material by relative movement between the centers of the roller dies which would result from flexing or vibrating shafting. Also, for best results, the dies should have a predetermined dimensional relationship with respect to each other, and with reference to the thickness of the material, as will be pointed out more fully hereinafter.

Reference is now made to the drawings for a more detailed description of the invention, in which:

Fig. 1 is a more or less schematic, fragmentary, longitudinal sectional view of a form of machine embodying roller die mechanism of my invention, taken in a plane indicated by line 1—1 in Fig. 2; the dies being shown out of proportion to illustrate them more clearly.

Fig. 2 is a fragmentary front elevation of the machine shown in Fig. 1.

Fig. 3 is a more or less schematic, fragmentary front elevation, illustrating additional bearing supports for the roller die shafting, which may be employed if such shafting is not of sufficiently large diameter to have substantially no vibration or flexing.

Fig. 4 is a transverse sectional view of the mechanism of my invention, taken in planes indicated by line 4—4 in Fig. 1.

Fig. 5 is an enlarged, schematic fragmentary view illustrating a roller contact length and roller diameter relationship for corrugated paperboard which has only one layer of corrugated paper. The view is approximately double scale.

Fig. 6 is an enlarged, schematic fragmentary view illustrating a roller contact length and roller diameter relationship for corrugated paperboard which has two layers of corrugated paper, often designated in the trade as "double double" board. This view is approximately one and two-thirds (1½) scale.

Fig. 7 is an enlarged, schematic fragmentary view, approximately double scale, illustrating preferred die dimensions for corrugated paperboard which has only one layer of corrugated paper.

Fig. 8 is an enlarged, schematic fragmentary view, approximately double scale, illustrating preferred die dimensions for the so-called "double double" corrugated paperboard.

Fig. 9 is an enlarged fragmentary sectional view of one form of corrugated paperboard before folding thereof, illustrating the type of crease formed by the roller die mechanism of my invention.

Fig. 10 is an enlarged fragmentary sectional view of the board of Fig. 9 folded to provide a right angle corner in a container or the like.

Fig. 11 is an enlarged fragmentary sectional view of folded "double double" paperboard having a crease formed by the roller die mechanism of my invention.

Fig. 12 is a schematic plan view, on a reduced scale, of a creased and slotted blank of paperboard adapted for folding into box or container form; the crease lines in this view being illustrated merely by dotted lines for clarity.

Fig. 13 is a fragmentary top elevation looking in the direction of arrow 13 of Fig. 9.

Fig. 14 is a fragmentary bottom elevation looking in the direction of arrow 14 of Fig. 9.

The roller die mechanism of my invention may be employed in place of roller knife scoring mechanism in well known forms of machines now employed by the industry for scoring or creasing corrugated paperboard. These machines usually contain mechanism for slotting the paperboard, and also printing mechanism, and are known to

the trade as "printer-slotters." Such machine usually comprises a framework 2 supporting conventional printing mechanism 3 which includes suitable power driven inking rollers 4. Conventional power driven slotting mechanism 6 is generally provided, which cuts out material from the blank 7 (Fig. 12) fed to the machine, to form slots 8 which, when the blank is folded along crease or hinge lines 9, form the top and bottom cover flaps 11 of the resulting container. Crease lines 9 preferably run transversely at right angles to the corrugations; and running substantially parallel to such corrugations are crease or hinge lines 12 which, when the blank is folded, provide the sides 13 of the resulting container.

Hinge lines 12 are formed by the roller die mechanism 14 which follows the slotting mechanism 6 in the type of machine illustrated; although the slotting mechanism may follow the roller die mechanism, which is the order in other types of machines. Hinge lines 9, being transverse to the direction of feed of the material in the machine illustrated, may be formed either beforehand or subsequently by another machine.

Roller die mechanism 14 comprises a pair of rotatable shafts 16 journaled in suitable bearings 17 and which are driven by any suitable driving mechanism 18, only a portion of which is shown, as such driving mechanism is conventional. Preferably, the bearings for one of the shafts are embodied in suitable adjustable eccentric mechanism 19, such as shown in United States Patents Nos. 2,030,027 and 2,030,028, both dated February 4, 1936, to provide for adjustment of the distance between the male and female dies on such shafts when this is desired. As was previously related, it is desirable that shafts 16, have substantially no vibration or flexing when they are driven, to avoid possible tearing of the material, which might otherwise occur if the roller dies had substantial relative movement with respect to each other when they are driven. To obtain this result, the shafts are made of sufficiently large diameter if they are provided with bearing support only at their ends. I have found that, for this purpose, the shafts, which are of the usual metal, should not be much less than six (6) inches in diameter in machines adapted to form a plurality of parallel hinge lines 12. The same result may be obtained with shafts of lesser diameter if they are provided with sufficient bearing supports 26 intermediate their length, as is shown in the modification of Fig. 3.

Each male roller die structure preferably comprises a die ring 27 having a continuous peripheral flange 28 which provides a male die member of a predetermined size to be described hereinafter. Preferably such die ring is split, and the parts thereof are fixedly but detachably secured to a split collar 29, by cap screws 31; the collar having a shoulder portion 32 on which the ring is seated, and the parts of the collar being fixedly clamped together about a shaft 16, by cap screw 33. Collar 29 may be additionally held against relative angular movement with respect to its mounting shaft, by key means 34 which permits axial adjustment of the die structure for forming the roller die crease at the desired location. In this connection, the detachable mounting of die ring 27 enables ready employment of any desired size die member 28, as one die ring may be easily interchanged or substituted for another by virtue of the described arrangement.

The construction of each female die structure is, preferably, the same as that of the associated

male die structure, except that die ring 36 thereof is provided with a peripheral slot or recess 37 which forms the female part of the die, which cooperates with male member 28 to form the roller die crease. Like reference characters are applied to the other parts of the female die structure corresponding to like parts in the male die structure. As with respect to the male die structure, each female die structure is axially adjustable, and the female die ring 36 is detachably mounted for the purpose described with reference to the male die ring 27.

In the embodiment of the machine illustrated, the male roller die mechanism is at the bottom. This position is immaterial, however, as the male roller die mechanism may be the top or at any other angular position with respect to female roller die mechanism, as the corrugated sheet material feeds between the dies, and it makes no difference at what angle the direction of the feed may be. In this connection, the shafts 16 are driven in opposite directions, generally at between eighty (80) and one hundred (100) revolutions per minute (R. P. M.); and to preclude tearing of the material, the gearing in driving mechanism 18 is such as to provide the same peripheral speeds of the male and the female roller die structures, i. e., the outer peripheral surface 38 of male die member 28 rotating at the same speed as peripheral surface 39 of female die ring 36.

It is important in order to avoid rupturing or tearing of the corrugated paperboard that the roller dies, especially the male roller die, be of sufficiently large diameter to provide a roller contact length on the paper board of at least five (5) times the over-all thickness of the board; such over-all thickness being the total width between the outer surfaces of the board. In commercial corrugated paperboard containing one layer of corrugated paper 41 (Figs. 9 and 10) adhesively united between outer layers 42 of plane paper, the over-all thickness T (Fig. 10) will usually vary from four thirty-secondths ($\frac{4}{32}$) to five thirty-secondths ($\frac{5}{32}$) of an inch, depending on the thickness of the individual layers of the paperboard and the height of the corrugations.

In creasing such board, the extent of projection of male die member 28 (Fig. 7) from peripheral surface 43 on the male roller, and the depth of female die slot 37 are such, that the distance between male peripheral surface 38 and the root face 44 of the female die, will effect pressure on the board sufficient to cause thorough compacting or compressing the material in slot 37 but insufficient to cause rupturing thereof. For board containing one layer of corrugated paper, such distance will generally be approximately one-third ($\frac{1}{3}$) of the over-all thickness of the board, with slight variations depending on the thickness of the individual layers of the paper forming the board and the height of the corrugations.

In this connection, the spacing between roller surfaces 39 and 43 on the center line C, is such that there will be substantially no driving contact on the material by such surfaces as the rollers are driven. Thus, this distance is preferably made slightly greater than the over-all thickness of the board. The previously described adjustable mounting of the roller dies relative to each other permits one to set up the machine readily for obtaining the desired spaced relationship between the dies.

To obtain the desired roller contact length, I have found that the female roller diameter should be sufficiently large to provide sufficient

bearing surface for the material. This diameter, however, is not particularly critical, because it is the male die roller which primarily effects the creasing, and causes penetration of the material into the female die 37. A diameter of at least about six (6) inches will be sufficient for the female roller. In creasing board having only a single layer of corrugated paper and an over-all thickness of about between four thirty-secondths ($\frac{4}{32}$) and five thirty-secondths ($\frac{5}{32}$) of an inch, the male roller should not be much less than seven (7) inches in diameter, although the greater this diameter is, the better, because the roller contact length will increase with increase in diameter of the male roller.

Fig. 5 illustrates a roller diameter relationship for corrugated paperboard having only one layer of corrugated paper and which has an over-all thickness of four thirty-secondths ($\frac{4}{32}$) of an inch. The female die roller is six (6) inches in diameter, the diameter being measured to the outer peripheral surface 39; and the male die roller diameter is eight (8) inches, the diameter being measured to the peripheral surface 38 of male die member 28. The depth of female recess 37 is preferably five sixty-fourths ($\frac{5}{64}$) of an inch, which is satisfactory for all commercial thicknesses of board.

It is to be noted that as the paperboard P, indicated by dotted lines, passes between the driven die rollers, it is moved by such rollers in a direction indicated by the direction arrows, and the portion of one surface of the paperboard not being creased, namely the portion outside but adjacent the creasing zone, engages female roller surface 39 adjacent the center line C joining the centers of the two rollers; and the opposite surface of the paperboard becomes initially indented or compressed in the creasing zone, by male die member 28, at the location L spaced from the center line C. The roller die crease will thus commence to be formed at location L; and such crease will continue to be formed during the entire distance D of travel of the paperboard between locations L and C which is the roller creasing contact length. With the over-all thickness of paper board mentioned and rollers of the diameter related, such distance D or the roller contact length, is about one (1) inch.

The same roller diameter relationship will be all right for corrugated paperboard having an over-all thickness of five thirty-secondths ($\frac{5}{32}$) of an inch, as the roller contact length will still be more than five (5) times the over-all thickness of the board. As was previously stated, it is desirable to have the diameter of the male roller die as large as practically possible; the dimensions referred to being merely by way of illustration.

In roller die creasing corrugated paperboard having two layers of corrugated paper, the diameter of the male roller die has to be greater than that for board having only one corrugated layer, because such paperboard has a greater over-all thickness. As is illustrated in Fig. 11, paperboard comprising two layers of corrugated paper 46 (called "double double" board in the trade), usually includes an inner layer 47 of plane paper, and also outer layers 48 of plane paper, all adhesively united together. The over-all thickness of such board will generally vary from ten thirty-secondths ($\frac{10}{32}$) to twelve thirty-secondths ($\frac{12}{32}$) of an inch, depending on the factors mentioned with reference to corrugated paperboard

having only one layer of corrugated paper. With board of this type, the male roller die should for best results be at least fourteen (14) inches in diameter, while the female roller die, although it may be as small as six (6) inches in diameter, should for best results be at least seven (7) inches in diameter.

Figs. 6 and 8 illustrate a roller die relationship for "double double" paperboard P having an over-all thickness of ten thirty-secondths ($\frac{10}{32}$) of an inch; the male die roller diameter being fourteen (14) inches, and the female die roller diameter being seven (7) inches. Because of the increased over-all thickness of board, the periphery 38 of male die member 28 should be spaced a slight distance from the female roller periphery 39, at center line C; the spacing being such as to cause thorough compacting of the material in the slot 37 without rupture thereof. Usually, such spacing will be approximately one-fourth ($\frac{1}{4}$) the over-all thickness of the board. In this connection, the depth of female recess 37 is preferably five sixty-fourths ($\frac{5}{64}$) of an inch, which, as was previously mentioned, is satisfactory for all commercial thicknesses of board. Thus, at center line C, the distance between male peripheral surface 38 and root face 44 of the female die, will be approximately one-half ($\frac{1}{2}$) the over-all thickness of the board.

The spacing, at center line C, between peripheral surfaces 39 and 43 of the dies should be approximately equal to the over-all thickness of the board but, preferably, slightly greater, so that these surfaces do not have substantial driving effect on the board. The roller creasing contact length, indicated by distance D, is about one and thirteen-sixteenths ($1\frac{13}{16}$) of an inch. In this connection, the male die roller may be larger if so desired because the greater the diameter thereof, the less rupturing effect there will be on the board as it is being creased.

When the machine embodies a plurality of laterally spaced cooperating pairs of the roller dies positioned side by side, as is usually the case, a lateral pull or stretching is imposed on the material as the male dies indent it into the female dies. To lessen this pull, and thereby minimize rupture which might otherwise result, it is desirable to have some of the male die members 28 of slightly less diameter. For this purpose, I preferably make every other male die member 28 about fifteen to twenty thousandths (0.015 to 0.020) of an inch less than the diameters of the other male dies. The same result may also be obtained, for example, by making the inside male dies of slightly less diameter than the outside male dies, or vice versa.

For best results, the width of the male and the female dies should have a predetermined relationship with respect to the over-all thickness of the corrugated paperboard. If the dies are too narrow in width, then when the board is folded along the resultant die crease, tearing and an unsightly hinge line may result. If they are too wide, the hinge will develop too much play when the board is folded, which is undesirable because the rigidity of the resulting container will be impaired, causing loss in strength. Preferably, the male die member 28 should have a width approximately equal to the over-all thickness of the board, and the female die recess 37 should have a width approximately twice the width of the male die, or in other words, approximately twice the over-all thickness of the board. Also, the male die member 28 should be centered with respect to

the female recess 37; so that substantially the same spacing obtains between each side of male die member 28 and the adjacent side of female recess 37.

Fig. 7 illustrates the preferred die dimensions for corrugated paperboard having a single layer of corrugated paper and an over-all thickness of five thirty-secondths ($\frac{5}{32}$) of an inch; male die member 28 being five thirty-secondths ($\frac{5}{32}$) of an inch wide, and female recess 37 being twice such width. In Fig. 8, the preferred dimensions are illustrated for "double double" board having an over-all thickness of ten thirty-secondths ($\frac{10}{32}$) of an inch; the male die member 28 having this width and the female recess 37 twice such width. This described die width relationship is preferred for best results, but may vary plus or minus one sixty-fourth ($\frac{1}{64}$) of an inch either way; so that the male die member width will still be substantially equal to the over-all thickness of the paperboard, and the female die recess width substantially twice the over-all thickness of the paperboard.

As can be seen from Figs. 9, 10, 13 and 14, the die crease results in positive indentation 51 of the material, forming depressed inner and outer surfaces of substantial width which results in a straight hinge edge for folding. The surface 52, which forms the inner surface of the container when the board is folded at a right angle, and which is acted upon directly by male die member 28, has two definite inner and parallel crease lines 53 below the plane of surface 52 and which are formed by the spaced edges or corners of male die member 28. These crease lines are spaced apart substantially the width of such male die member 28, which is substantially the over-all thickness of the material. Crease lines 53 are between outer parallel crease lines 54 which are formed by the pressure acting against the edges or corners of the female die recess 37; the crease lines 53 and 54 being joined by flat surfaces 55 which have relative outward slant with reference to the depressed portion of surface 52. Because of the pull on surface 52 effected by the dies, the distance between crease lines 54 will be somewhat less than twice the over-all thickness of the material, depending on the pressure.

Surface 57 of the board, which forms the outer surface of the container when the board is folded at a right angle, and which is acted upon directly by the female die part 37, has two definite parallel crease lines 58 which are spaced apart a distance substantially twice the over-all thickness of the paperboard because they are formed by the edges or the corners of the female die part 37. As a result of the described creasing, the walls adjacent the crease may be folded at a right angle with respect to each other to form a rigid and true or straight corner, as is illustrated in Fig. 10. Also, such walls may be folded against each other, for shipping or storage purposes, without tearing of the hinge or crease line.

The same crease line arrangement and proportional relationship will be formed on the "double double" board which is shown with a right angle fold in Fig. 11; and the same reference characters are, therefore, applied in this view.

Because of the positive parallel crease lines and the positive indentation of the board that are formed by the dies of my invention, a hinge connection obtains which permits folding of the container blank into container form without any bulging of the sides, making for a nice appearing as well as strong container. In this connection,

the described male and female die relationship with respect to each other, and with respect to the over-all thickness of the board may be utilized in so-called bar creasing mechanism, comprising elongated relatively reciprocating male and female dies, and produce my desired type of crease or hinge in corrugated paperboard.

I claim:

1. Roller die creasing mechanism for corrugated paperboard comprising a male roller die and a female roller die, the male roller die including a male die member having a width substantially equal to the over-all thickness of the paperboard, and the female roller die having a die recess the width of which is substantially twice the width of the male die member.

2. Roller die creasing mechanism for corrugated paperboard comprising a male roller die and a female roller die, the male roller die including a male die member having a width substantially equal to the over-all thickness of the paperboard, and the female roller die having a die recess the width of which is substantially twice the width of the male die member, the diameter of the male roller die member being such as to provide a roller contact length on the board of at least five (5) times the over-all thickness of the board.

3. Roller die creasing mechanism for corrugated paperboard comprising a male roller die and a female roller die, the male roller die including a male die member having a width substantially equal to the over-all thickness of the paperboard, and the female roller die having a die recess the width of which is substantially twice the width of the male die member, the diameter of the male roller die member being such as to provide a roller contact length on the board of at least five (5) times the over-all thickness of the board, and means mounting such roller dies against substantial vibratory movement relative to each other when they are driven.

4. Roller die creasing mechanism for corrugated paperboard comprising a plurality of pairs of cooperating male and female roller dies positioned side by side to form a plurality of parallel creases in the board, some of the male roller dies being slightly less diameter than the other male dies to minimize pull on the material as it is being creased.

5. Roller die creasing mechanism for corrugated paperboard comprising a plurality of pairs

of cooperating male and female roller dies positioned side by side to form a plurality of parallel creases in the board, some of the male roller dies being of slightly less diameter than the other male dies to minimize pull on the material as it is being creased, and the diameter of each male roller die being such as to provide a roller contact length on the board of at least five (5) times the over-all thickness of the board.

6. In die creasing mechanism for corrugated paperboard, a male die member and a cooperating female die member, the male die member having a width substantially equal to the over-all thickness of the board, and the female die member having a die recess the width of which is substantially twice the width of the male die member.

7. In roller die creasing mechanism for corrugated paperboard, opposed rollers between which the board is passed, a female die groove formed in one roller, and a cooperating male die tongue formed on the other roller, the depth of said tongue exceeding the depth of said groove sufficiently to compress the board between the die parts without establishing driving contact between the board and the peripheral surfaces of the rollers, said male die tongue having a width substantially equal to the thickness of the paperboard, and the female die groove being substantially twice the width of the male die tongue.
